UNITED STATES PATENT OFFICE.

JOHN W. McAULIFFE, OF PROVIDENCE, RHODE ISLAND.

COLLAR-BUTTON.

SPECIFICATION forming part of Letters Patent No. 679,157, dated July 23, 1901.

Application filed June 20, 1900. Serial No. 20,961. (No model.)

To all whom it may concern:

Be it known that I, JOHN W. McAULIFFE, a citizen of the United States, residing at Providence, in the county of Providence and 5 State of Rhode Island, have invented a new and useful Improvement in Collar-Buttons, of which the following is a specification.

This invention has reference to an improvement in collar-buttons, and it consists in the 10 peculiar and novel construction and the combination of parts whereby a spring-pin is secured to the head of the button for the purpose of fastening the necktie or scarf to the collar-button, as will be more fully set forth 15 hereinafter.

Figure 1 is a side view of a collar-button containing my invention. Fig. 2 is an end view of the same. Fig. 3 is a side view, partly 20 in section, showing the construction of the head of the collar-button, the pin, and the safety device for protecting the point of the pin. Fig. 4 is a transverse sectional view of part of the head of the button, showing the 25 construction of the safety-latch protecting and holding the pointed end of the pin.

In the drawings, *a* indicates the shank of the collar-button, *b* the shoe, and *c* the head of the collar-button. In the construction of this collar-button the end of the shank is 30 flanged outward to form the annular flange *a'*. The head is formed of sheet metal, which is stamped in a die to give it its convex or spheroidal form. In making this head I stamp out a hole *c'* near the peripheral edge 35 of the head for the reception of the wire *c²*, forming part of the spring-pin *c³*, and also punch out the slots *c⁴ c⁴* and raise the convex shield *c⁵*, which forms the safety-fastening for the end of the spring-pin *c³*. In securing this

head to the shank I place the disk *c⁶* on the 40 annular flange *a'* and secure the wire *c²* to the disk, preferably by solder, and then roll or burnish the edges of the head *c* under the annular flange *a'* to secure the head to the shank. When the safety-pin is to be used, a slight 45 pressure on the pin permits the point to be moved laterally to one or the other of the slots *c⁴*, when the pin, being released, will assume the position shown in broken lines in Fig. 3. The necktie may now be secured on the pin *c³*. 50 A slight pressure on the pin carries it through one of the slots *c⁴*, and under the concavo-convex shield *c⁵*, thereby locking the pin and protecting the point against injury.

Having thus described my invention, I claim 55 as new and desire to secure by Letters Patent—

The combination with the shank of a collar-button having the annular flange *a'*, of the disk *c⁶*, the wire *c²* secured to the disk, the 60 spheroidal head *c* formed of sheet metal and perforated to form the opening *c'* for the insertion of the wire *c²*, the slots *c⁴ c⁴*, the concavo-convex safety - shield *c⁵*, integral with the 65 sheet metal of the head, and the spring-pin *c³*, formed integral with the wire *c²*, whereby the pin is flexibly connected with the head and adapted to secure the wearing-apparel to the head while the point of the pin is covered, as described. 70

In testimony whereof I have signed my name to this specification in the presence of two subscribing witnesses.

JOHN W. McAULIFFE.
